UNITED STATES PATENT OFFICE.

MICHAEL F. GOSSWILLER, OF TROY, MONTANA, ASSIGNOR OF ONE-HALF TO JOHN DELANEY, OF WHITEFISH, MONTANA.

DEVICE FOR REBRASSING FREIGHT-TRAINS.

1,034,359.

Specification of Letters Patent. Patented July 30, 1912.

Application filed October 18, 1911. Serial No. 655,332.

To all whom it may concern:

Be it known that I, MICHAEL F. Goss-
WILLER, a citizen of the United States, re-
siding at Troy, in the county of Lincoln
5 and State of Montana, have invented a new
and useful Device for Rebrassing Freight-
Trains, of which the following is a specifi-
cation.

This invention pertains to improvements
10 in devices or appliances for removing
brasses from journal boxes, especially of
car-wheels.

The invention has for its object to pro-
vide for readily and expeditiously removing
15 a journal box for effecting the displacement
of a worn-out brass.

A further object is to provide for effect-
ing the aforesaid result by the aid of the
action or turning of the car-wheel.

20 A still further object is to carry out the
aforesaid ends in a simple, inexpensive and
effective manner.

The invention consists of certain instru-
mentalities and features substantially as
25 hereinafter fully disclosed and defined by
the claims.

In the accompanying drawing, illustrating
the preferred embodiment of my invention
0 wherein it will be understood that va-
rious changes and modifications may be
made as relates to the detailed construction
and arrangement of the parts without de-
parting from the spirit thereof, Figure 1
5 is a broken and partly sectional perspective,
disclosing my invention as applied to a car-
wheel and its journal-box for practical use,
as in displacing a worn-out brass or an in-
effective one resulting from a hot box. Fig.
10 2 is a side view of the same, certain parts
being broken away, with the parts in initial
position. Fig. 3 is a like view of the same,
the parts being in final position, as when
the journal box has been pried or lifted
so as to allow of the displacement or re-
15 moval of the brass, and the same substi-
tuted by a new one. Fig. 4 is a broken de-
tailed perspective of the hanger-member for
engaging the journal-box. Fig. 5 is an
edge elevation of the device, with the
20 bracket or clamp-member engaging the car-
wheel, the latter being shown in section, and
the hanger-member engaging the journal-
box.

In carrying out my invention, I suitably
provide a bracket or clamp 1 and a hanger 2

for conjoint or coöperative action for the
purposes herein named. The bracket or
clamp 1 is hook-ended, as at 3, to provide
for its engagement over the perimetric edge
of a car-wheel as illustrated, while its oppo-
site end is terminated into a cylindrical stud
4 which is received by a circular aperture 5
in the upper end of the hanger 2 to allow it
to turn more or less therein and yet enable
the bracket or clamp to actuate said hanger 60
by the movement of the car-wheel, as pres-
ently seen. The hanger 2 is preferably an-
gular in outline to allow of its upper end
being moved to a position about centrally
alining the wheel as seen in Fig. 3 as the 70
car-wheel is turned in the direction of the
arrow, it being understood, of course, that
the hanger is engaged with the journal-box
during such movement of the car-wheel.
Said hanger has an upwardly facing or pre-
75 sented lug or shoulder 6 offset therefrom and
adapted to take under the opposite bottom
edge of the journal-box as disclosed in most
of the figures of the drawing.

It is observed that, in event of an emer-
gency, as should it become necessary to re-
move or displace a brass, which may have
become ineffective, or burned out, by suit-
ably applying the clamp or bracket and
hanger to the journal-box and car-wheel, 85
respectively, and starting up the engine or
locomotive, the movement thus imparted to
the car-wheel will carry the bracket or
clamp and hanger to the position as indi-
cated in Fig. 3. This movement of parts 90
will have the effect, it is evident, to lift the
journal-box, when the burned out or in-
effective brass is readily accessible for re-
moval and renewal. It is, of course, only re-
quired to reverse the aforesaid movement, 95
in order to dispose the journal-box, with its
brass, into normal position, when the appli-
ance is readily removed from the journal-
box, and car-wheel and the same placed
aboard the train for subsequent use when-
ever such may arise. It is also observed
100 that, as this device exerts a binding action
upon the car-wheel when the parts have at-
tained the position as indicated in Fig. 3,
or have become effective, the further move-
ment of the train will not result in turning
105 the wheel but the wheel being thus locked
will only skid along the rail, consequently,
no predetermined or specified adjustment is
required for said appliance, also that the 110

appliance is automatic in action, as is apparent from the foregoing disclosure.

What is claimed is:—

1. A device of the type described, includ-

hanger having an opening in its upper end pivotally receiving said stud, the lower end 20 of said hanger having an upwardly facing shoulder, offset therefrom and adapted to
